DRAFT REGULATOR

Clarence H. Morrow, Shaker Heights, Ohio, assignor to The Hotstream Heater Company, Cleveland, Ohio, a corporation of Ohio

Application February 24, 1933, Serial No. 658,393

2 Claims. (Cl. 236—45)

This invention relates to dampers such as are employed for automatic draft regulation, for improving the operation of furnaces. An example of such a device is that shown in my copending application, Serial No. 443,767, filed April 12, 1930, and the objects of this invention are generally to improve the draft regulator there shown.

More specifically it is an object of this invention to strengthen the shutter employed, that the shutter may be of light weight, as of sheet metal, yet have sufficient strength though of large size.

A further object of the invention is to provide that the device be adapted for application in either of two arrangements, in an opening leading to a draft passage, dependent upon the direction of flow therein.

The exact nature of this invention together with further objects and advantages thereof will be apparent from the following description taken in connection with the accompanying drawings, in which Fig. 1 is a view in elevation of an embodiment of the device, taken as from the back when the device is installed; Fig. 2 is a detail section as in the plane of line 2—2, Fig. 1; Figs. 3, 4 and 5 are enlarged sectional details as in the planes of lines 3—3, 4—4 and 5—5, respectively, Fig. 1; and Figs. 6 and 7 are views in elevation illustrating characteristic installations of the device wherein flow is had in opposite directions.

With reference now to the drawings, the principal parts of the regulator are an annular base 1 and a damper or shutter 2.

The base 1 may be of cast metal bearing on one face the legends indicated in Figs. 6 and 7, and a ferrule flange 3. At its opposite face it is preferably tapered as at 4, that it may be conveniently inserted into the end of a circular pipe 5. The base is provided with radial openings to receive means for securing it with the pipe, such as the screws 6, and the bosses indicated at 7 may be provided at the openings.

The base also is provided with a pair of inwardly extending bosses 8 oppositely but not diametrically disposed, to receive plugs 9 bearing the sockets indicated on their inner faces.

The legend on the front face of the base includes means providing an index to fix the proper position of the base when the latter is to be installed in its pipe, as will appear. The word "Top" appearing at 10, Fig. 6, serves this purpose. The bosses 8 are so related with the index 10 that when the base is plumbed with this index on top, the bosses 8 will define a line 11, in Fig. 6,

in the general plane of the base but sloping sharply from the horizontal.

The face of the base carries a second index 12 so angularly disposed from the first index 10 that when the base is disposed plumbed to its second index 12, the bosses 8 will define a line 13, Fig. 7, having the same slope as the line 11 but in the opposite direction.

The damper 2 is preferably of sheet metal having a peripheral rearwardly turned flange 14, and of such diameter as to fit within and substantially close the circular opening in the base 1. On the rear face of the damper 2 are secured a pair of blocks 15 located near the damper periphery correspondingly with the bosses 8. Each block 15 carries a plug 16 having an outwardly extending projection 17 adapted to fit into the socket of one of the plugs 9. By this arrangement and as indicated Figs. 1 and 4, the damper may be mounted in the base 2 to swing in the base opening on an axis extending generally between the bosses 8, and the damper centered with the base. That the damper may effectively close the base opening, and swing in only one direction from the plane of the base, the latter is provided with a flange 18 back of the damper on the short side of the bosses 8 and a flange 19 in front of the damper on the long side of the base from the bosses 8.

A brace member 20 is secured on the front face 30 of the damper, extending between the bearing blocks 15 and secured, through the damper, with the blocks, as by the rivets indicated.

The back of the damper is also provided with brace means having a body part 21, arms 22 at 35 its ends, and arms 23 intermediate its ends. This brace means is preferably a casting, its body part 21 of channel section, and its arm parts of T-section, these sections being provided by the integral flanges indicated in the drawings. The body part 21 is disposed diametrically of the damper, at right angles to the brace 20. Its end arms 22 are adjacent the peripheral flange 14 of the damper and secured to the damper as by the rivets indicated. The intermediate arms 23 lie 45 opposite the brace 20 and are secured to the latter by rivets passing through suitable openings in the damper, as indicated.

Thus the two brace means on opposite faces of the damper, are in cruciform relation and serve 50 as ribs which, together with the peripheral flange 14 give great rigidity to the damper.

Cylindrical weights 24 are secured to the rear face of the damper and so proportioned that the latter including its parts thus far described, 55

is substantially balanced on its described axis of swing.

The body part of the brace 21 is provided with a pair of bosses 25 rearwardly extending to carry back of the damper a rod 26 threaded throughout its length and secured in the bosses. A weight 27 is threaded upon this rod for adjustment therewith by rotation. The proportioning and arrangement of the parts is such that the weight 10 27 is adjustable between a position back of the brace 20 and hence without substantial effect upon the balance of the damper about its axis, and a position at the periphery of the damper, on the long stretch of the latter from the axis, 15 in which position the weight has most effect to unbalance the damper.

With reference now to Figs. 6 and 7, and first to Fig. 6, the draft regulator is shown as applied to a line wherein the flow of draft, as from furnace to stack, is from left to right. The legend on the base 1 includes indicia for the direction of draft as indicated, so that the proper index 10 20 12 will be selected as the one to be at the top. Thus when the base is installed as shown, the long stretch of the damper, which swings inwardly from the base, will move generally in the direction of flow.

As indicated Fig. 7, if the draft be right to left, the base is disposed so that its other index 12 30 is at the top, in which case the damper will swing in the opposite direction. These arrangements of the damper swing are the necessary ones for proper regulation, as will be appreciated by one familiar with the art; and are obtained it will 35 be noted, without any change in relation between the damper and its base.

What I claim is:

1. In an automatic damper of the class described, and having an annular base and a shutter adapted to control the opening of said base, brace means for said shutter comprising a pair of members arranged in cruciform relation on the opposite faces of the shutter and each secured to the latter, one of said brace members being nondiametrically disposed and having bearing means at its ends arranged to mount said shutter on said base for swinging movement, the other brace member being diametrically disposed and having a weight mounted for adjustment therewith, said diametric brace member having arms extending therefrom at its ends and secured at 10 their ends with said shutter, and also having arms opposite said other brace member and secured to the latter through openings in said shutter.

2. In an automatic damper of the class described, and having an annular base and a shutter adapted to control the opening of said base, brace means for said shutter comprising a pair of members arranged in cruciform relation on the opposite faces of the shutter and each secured to the latter adjacent its extremities and to the other brace member intermediate said extremities, one of said brace members being nondiametrically disposed and having bearing means at its ends arranged to mount said shutter on said base for swinging movement about an axis substantially along said nondiametric brace member, the other brace member being diametrically disposed and having a weight mounted for adjustment thereon toward and from said axis. 20 25 30 35

CLARENCE H. MORROW.
